UNITED STATES PATENT OFFICE.

WILLIAM ERASTUS WILLIAMS, OF CHICAGO, ILLINOIS.

MEANS FOR STIFFENING SHEETS OF METAL AND OTHER MATERIAL.

1,191,863.

Specification of Letters Patent. Patented July 18, 1916.

Application filed November 9, 1914. Serial No. 871,033.

To all whom it may concern:

Be it known that I, WILLIAM ERASTUS WILLIAMS, a citizen of the United States, residing at Chicago, county of Cook, and State of Illinois, have invented a new and useful Improvement in Means for Stiffening Sheets of Metal and other Material, as set forth in the annexed specification.

The object of my invention is to so emboss a sheet of metal that the sheet will be very stiff in every direction and at the same time be equally stiff in each direction and the invention is set forth in the claims.

Reference will be had to the accompanying drawings in which—

Figure 1 is an elevation of a wall siding of sheets embossed in accordance with my invention. Fig. 2 is a transverse sectional view of the structure shown in Fig. 1. Fig. 3 shows a marginal finish for a sheet. Fig. 4 shows another form of margin for a sheet. Fig. 5 shows a marginal finish developed from Fig. 4. Fig. 6 shows another marginal finish developed from Fig. 4.

25 In the drawing 1 indicates sheets of metal or other suitable material capable of being embossed.

2 2 indicates cup shaped bosses pressed into the sheets at suitable intervals.

30 3 indicates ribs that run along lines intersecting each other at the centers of the bosses.

35 The cups are approximately twice as deep as the ribs and both are embossed in the same direction from the surface of the sheet. Thus the bending moment of resistance is as great across the cups in any direction as it is across the ribs transversely of any rib or line across the sheet or more specifically the 40 bending moment of resistance is as great across line A—A as it is across line B—B, Fig. 1, and the same is true across corresponding lines transversely of the sheet. Thus by my construction, I secure a sheet 45 equally stiff in both directions.

In using my stiffened sheets for sheathing of any kind, laps may be made as is indicated by the sheets 4, 5 and 6.

50 When my sheets are used as separate panels, for doors and similar purposes, I stiffen and finish the edges by bending a large rib along the edge approximately as deep as the cups, and 7, in Fig. 3, indicates such a marginal rib.

Fig. 4 shows a rib with a flange 8 extending above the body of the sheet on the opposite side of the sheet from the ribs and bosses. This flange may be pressed up tightly closing the space 9, Fig. 4 so that it will appear like the rib 10, Fig. 6 and the flange 8 may be bent over upon the body of the plate as indicated by 11 Fig. 5 and then riveted or spot welded to the sheet as indicated by 12, Fig. 5.

In place of closing space 9, Fig. 4, it may be allowed to remain open and still turn over the flange 8 so that it will appear as is indicated by 13, Fig. 6 and it may be welded or riveted to the plate as indicated by 14.

This structure may be used for such articles as carpet-lining, mailing board and various articles made out of paper pulp or kindred materials, and may be used for articles made out of celluloid, gelatin and various other materials, but its chief use will be with metals.

The ribs may extend in various directions instead of perpendicularly to each other as shown in the drawing.

What I claim is:

1. A sheet, consisting of material adapted to be molded or pressed and to afford strong resistance to distortion when formed, provided on one face with two series of hollow ribs or corrugations of substantially uniform cross section extending along intersecting sets of lines and merging into higher bosses located at the points of intersection, respectively.

2. A sheet, consisting of material adapted to be molded or pressed into desired form and to strongly resist distortion when formed, provided on one face with hollow ribs or corrugations running along intersecting sets of lines and merging into hollow bosses higher and broader than the ribs.

3. A metal sheet of substantially uniform thickness having pressed up from one face ribs running along intersecting sets of lines and higher and broader bosses into which the ribs merge near the points of intersection.

4. A sheet, consisting of material adapted to be molded or pressed and to afford strong resistance to distortion when formed, provided upon one face with two series of hollow ribs or corrugations, of substantially uniform cross section from end to end, ex-

tending along intersecting sets of lines and
merging into higher bosses located at the
points of intersection, respectively, and fur-
ther provided with marginal ribs in which
the said sheet is bent sharply upward and
doubled back upon itself, substantially as
set forth.

In witness whereof, I have hereunto signed
my name at Chicago, Illinois, on the 29th
day of October, 1914.

WILLIAM ERASTUS WILLIAMS.
